US0D1081587S

(12) **United States Design Patent** (10) **Patent No.:** **US D1,081,587 S**
(45) **Date of Patent:** **** Jul. 1, 2025**

(54) **POWER STRIP**

(71) Applicant: **Zhuhai Tessan Power Technology Co., Ltd.**, Guangdong (CN)

(72) Inventors: **Zihua Yu**, Guangdong (CN); **Guiming Wang**, Jilin (CN)

(**) Term: **15 Years**

(21) Appl. No.: **29/984,955**

(22) Filed: **Jan. 15, 2025**

(51) **LOC (15) Cl.** **13-03**

(52) **U.S. Cl.**

USPC **D13/139.8**

(58) **Field of Classification Search**

(57) **CLAIM**

The ornamental design for a power strip, as shown and described.

DESCRIPTION

FIG. 1 is a front perspective view of a power strip showing my new design.

FIG. 2 is a rear perspective view thereof.

FIG. 3 is a front view thereof.

FIG. 4 is a rear view thereof.

FIG. 5 is a left side view thereof.

FIG. 6 is a right side view thereof.

FIG. 7 is a top view thereof; and,

FIG. 8 is a bottom view thereof.

The broken lines illustrate portions of the power strip that form no part of the claimed design.

1 Claim, 8 Drawing Sheets
